SANITARY CLOSET DEVICE

Robert L. Williamson, Erwin, Tenn.

Application October 9, 1934, Serial No. 747,541

3 Claims. (Cl. 4—251)

This invention relates to toilet seats and more particularly to a cover for a toilet seat.

An object of this invention is to provide in a structure of this kind means whereby the cover 5 of the toilet may be raised by the weight of the person and the cover maintained in upraised position by weight placed on an operating member disposed forwardly of the seat.

Another object of this invention is to provide 10 in a structure of this kind means whereby a relatively small movement of the cover operating member will effectively swing the cover through an arc of substantially 90° so as to raise the cover from a horizontal position to a vertical 15 position.

The above and various other objects and advantages of this invention will in part be described and in part be understood from the following detailed description of the present preferred embodiment, the same being illustrated in the accompanying drawing wherein:—

Figure 1 is a top plan view of a device constructed according to the embodiment of this invention.

Figure 2 is a sectional view taken on the line 2—2 of Figure 1, showing the cover in closed position.

Figure 3 is a view similar to Figure 2 of the lid in open position.

Referring to the drawing wherein like numerals designate corresponding parts throughout the several views, the numeral 10 designates generally a platform having a front wall 11 secured thereto and a floor 12 extending forwardly of the front wall 11. A toilet seat structure, generally designated as 14, is mounted on the platform 10 and a lid or cover 15 engages the seat structure 14.

In order to provide means whereby the lid 15 may be raised and held in raised position, I have provided a crank 16 which, in the present instance, is integral with the pintle 13 of the lid 15 and the pintle 13 is journaled in bearings 17 disposed one on each side of the inner end of the lid 15. The pintle is fixed relative to the lid 15 so that turning of the pintle will also swing the lid. A spring 18 is disposed about the extended end of the pintle 13 and has one end thereof secured to or engaging against the adjacent bearing 17 and the opposite end of the spring 18, as shown in Fig. 1, engages the crank arm or lever 16 so as to constantly urge the crank arm 16 and the lid 15 to closed position.

A treadle, generally designated as 19, is hingedly secured to a plate 20 by means of a pintle

21. The rear or inner end of the treadle 19 is provided with an upturned flange 22 and an arm 23 is secured beneath the treadle 19 and extends inwardly thereof.

A lever 24 has one end thereof pivotally secured to the floor 12 as by bearing means 25 in the form of a pair of L-shaped angle bars and the opposite end of the lever 24 is free and extends parallel with the vertical wall 11.

A flexible member 26 has one end thereof secured to the free end of the lever 24 and this flexible member extends vertically from the free end of the lever 24 and enters a horizontally disposed opening 27 provided in one side of the seat structure 14. A pulley 28 carried by a flanged U-shaped member 29 is mounted in the forward portion of the seat structure 14 so that the flexible member 26 may be trained over this pulley 28 and loosely moved through the opening 27. The rear or other end of the flexible member 26 is secured to the crank lever 16 so that when the pedal 19 is depressed, the crank 16 will be rocked and the seat cover 15 raised. The arm 23 is pivotally connected to the lever 24 at a point adjacent the inner or pivoted end 25 of the lever 24 so that a slight movement vertically of the treadle 19 will cause a movement at the free end of the lever 24 sufficient to swing the cover 15 from a substantially horizontal position to a vertical position.

In the use of the device herein disclosed, when a weight such as a foot or the like is placed on the treadle 19, this treadle is depressed and a vertical movement in a downward direction is transmitted to the lever 24, thereby pulling the flexible member 26 downwardly and rocking the crank 16 downwardly against the tension of the spring 18 and raising the cover 15. When the person steps off of the treadle 19 or removes the weight, the spring 18 will act to 40 lower the cover 15 and at the same time will raise the treadle 19 to an inoperative position by a person whereby depressing of the treadle 19 will cause the cover 15 to be lowered.

It will also be apparent from the foregoing 45 that the cover operating means may readily be used with closet structures at present available and I, therefore, do not wish to be limited to the specific structure of a seat or closet shown.

What is claimed is:—

1. A sanitary device as set forth, comprising a seat having a horizontally disposed opening therethrough, a cover hinged to said seat, a treadle member rockably mounted forwardly and downwardly of the seat, a rock arm fixed rela- 55

tive to the cover, a rock lever disposed adjacent the free end of the treadle, means connecting the lever with the treadle, and a flexible member extending through said opening and connecting the free end of the lever with the rock arm to raise the cover coactive with the depression of the treadle.

2. A sanitary device as set forth, comprising a seat, a cover for the seat, hinge means including a crank arm for rockably mounting the cover on the seat, a spring constantly urging the cover to closed position, a pivoted treadle disposed forwardly and downwardly of the seat, a lever having an end thereof rockably mounted adjacent the free end of the treadle, pivotal means connecting the inner end of the treadle with the lever at a point intermediate the ends of the lever, and a flexible member connected at one end to the free end of the lever and at the other end to the crank arm whereby to raise the cover upon depression of the treadle against the tension of the spring.

3. A sanitary device as set forth, comprising a seat, a cover, means for rockably mounting the cover on the seat, said means including a crank arm, a spring constantly urging the cover to closed position, a treadle rockably mounted forwardly and downwardly of the seat, a lever having one end thereof rockably mounted rearwardly of the free end of the treadle, an arm connected to the treadle and pivotally engaging the lever intermediate the ends of the lever to lower the lever upon depression of the treadle, a pulley secured to the seat, said seat having a longitudinally extending channel therein and a flexible member extending through said channel and trained over the pulley, said flexible member having one end thereof connected to the free end of the lever and the other end to said crank arm whereby to raise the seat against the tension of the spring upon depression of the pedal.

ROBERT L. WILLIAMSON.
